UNITED STATES PATENT OFFICE.

WARD TEMPLE MIXSELL, OF WASHINGTON, DISTRICT OF COLUMBIA.

CARBURETER.

1,092,282.

Specification of Letters Patent. Patented Apr. 7, 1914.

Application filed April 10, 1911. Serial No. 620,186.

To all whom it may concern:

Be it known that I, WARD TEMPLE Mixsell, a citizen of the United States, residing at Washington, District of Columbia, have 5 invented certain new and useful Improvements in Carbureters, of which the following is a specification.

This invention relates to improvements in such apparatus as are intended to associate 10 definite amounts of hydrocarbons with free air to render a mixture of the same combustible within the cylinder of an internal combustion engine.

In the accompanying drawings—Figure 15 1 is a vertical section of the carbureter. Fig. 2 is a section on the line 2—2 of Fig. 1. Fig. 3 is a section on the line 3—3 of Fig. 1.

In the drawings, 1 indicates a top casing which incloses a medium pressure air chamber 20 33.

2 is a middle plate, 3 is the oil chamber and 4 its bottom plate.

5 is an inverted cup shaped differential valve which is pressed above by a spring 6 25 which may be compressed by a valve rod 7 which extends downwardly through the valve and through a guide 30. Said rod carries at its lower end a throttle valve 8 which controls the air inlet to a high pressure air chamber 31, under the middle plate 2. The valve rod 7 works through a guide 30 and has stop nuts 7' thereon, to limit its motion. An operating lever 10 is connected to the valve rod, by means of pins 9, and 30 said lever may be operated by any suitable means. The cup valve 5 incloses a nozzle 32 projecting from the middle plate 2, the capacity of the nozzle being substantially equal to that of the space between the nozzle 35 and the cup valve, as more fully explained 40 hereinafter. A baffle plate 34 is interposed between the valve 5 and the outlet from the carbureter.

38 is an annular wall or chamber depending 45 from the top of the casing 1 and leading to the outlet 39 which will be connected to the intake pipe to the cylinder. Air passes from the chamber 33 to the chamber 39 through an annular space 35 at the bottom, 50 between the lower edge of the chamber 38 and the outer surface of a rim 35', of smaller diameter, projecting upwardly from the plate 2 and around the spray nozzle, where-

by air flowing from the chamber 33 into the passage 38 enters the latter in the form of 55 an enveloping cylinder.

12 is a frusto-conical spray head mounted at the top of a rod 12' which extends through an opening in a cam spring 13, and said rod is connected to a spring 16, fastened near 60 the fixed end of said cam spring, on the underside thereof, the stem being clamped to the spring 16 by nuts 17. The cam spring 13 is fastened at one end to the wall of the oil reservoir by a bolt 18 and at the other 65 end is connected to a rod 14', which has a nut 19 thereon under the end of the spring. The spring may be fixed at adjustment by a set screw 15 which screws through the wall of the reservoir and is integral with the rod. 70 The oil pressure under the spray head is approximately equal to the total differential pressure less that due to the difference in level of the oil reservoir and the spray head, and if the differential pressure is varied the 75 pressure against the spray head will be correspondingly varied, and if a simple spring were used to control the movement of the spray head the degree of flexure of the spring would vary as the pressure against the head, 80 which would permit too great an opening of the oil valve, so it is necessary to interpose a progressively increasing resistance to limit the spring flexure, to obtain the desired opening and oil discharge. I ac- 85 complish this by causing the spring 16 to act against the cam 13. This spring cam 13 has a very slight rise which may be increased or decreased by the adjusting rod 14, but at any adjustment the spring cam will 90 form a curve, and as the spring 16 bends upwardly against the same in consequence of the lift of the stem 12' the point of contact will advance along the cam and thus progressively shorten the effective length of the 95 spring 16 and thus increase its resistance accordingly. If a permanently formed cam were used its degree of curvature would only be correct for one adjustment, but by using a rather heavy spring for a cam it may be adjusted by the rod, to take a new form and vary its curvature for each adjustment.

14 is the oil tube extending from the oil reservoir to the spray head. It will be noted that the diameter of said outlet is somewhat 100 less than the diameter of the spray head,

so that the inclined surface of the latter overhangs or extends beyond the rim at the mouth of the oil tube.

36 is an annular air port which surrounds the spray head and communicates from the high pressure air chamber 31 to the low pressure chamber 38.

The oil chamber is air tight, except for a hole 37 in the top, which admits pressure from the chamber 31, whereby the pressure in the oil chamber is always equal to that in the air chamber 31. The oil chamber is provided with a suitable float 20 controlling the feed to maintain a constant level therein by any suitable or old arrangement such as a float valve 26, float lever 25 and oil pipe 24. The oil tube 14 forms a guide for the valve rod 12', by means of vertical ribs 22.

20 It will be seen that there are two passages from the main air inlet port to the outlet pipe 38, one through the high pressure chamber 31 and air nozzle 36, and the other through the differential valve 5, medium pressure chamber 33, and annular passage 35, the chamber 33, being in effect, a valved by-pass between the air inlet and the low pressure chamber or outlet.

As will be observed this carbureter has 30 five specific structures each of which performs a special function. The function of the primary valve 8 at the inlet port is to effect a reduction of air pressure within the carbureter. The oil reservoir in other carbureters is subject to atmospheric pressure at all times, but in my carbureter, is closed to the atmosphere and has an air passage or port 37 opening from the pressure chamber 31. This serves to avoid an excess flow of 40 oil when the pressure within said chamber is reduced. The function of the automatic valve 5 is to cause a difference of pressure between the oil reservoir and the mixing chamber 38, to effect a flow of oil to the 45 atomizing device, and also to generate by such difference of air pressure a sufficient velocity of air through the nozzle 36 to effect atomization. The purpose of the spray head and adjacent parts is to effect atomization 50 and the regulation of the amount of oil atomized according to requirements. To prevent the liquid particles being precipitated upon the walls of the vacuum chamber 38 or other surfaces, is the function of the 55 secondary air current, drawn in through the annular passage 35, which, being of considerable volume, and being admitted to the vacuum chamber at the bottom and flowing upwardly forms a wall of dry air between 60 the central current (rising from the nozzle 36 and spray head) and the wall of the chamber 38, and carries the liquid particles through the intake pipe to the motor cylinder. In those carbureters in which the 65 throttle valve, baffle plates, or other devices

are located between the spray nozzle and the cylinder, this result is defeated, which is one of the reasons I put the throttle at the intake, and have the passage beyond the nozzle unobstructed.

The function of the automatic valve 5 in my carbureter is that of a differential pressure valve, to cause that difference of pressure in the upper and lower chambers required to effect atomization, as the oil will flow to the spray-head in greater amount as the differential pressure is increased, and as the major volume of air to support combustion must pass this valve, it is necessary that this valve should be of such a form as will pass a 70 definite volume of air for each definite increase or decrease in pressure, in order that a volumetric relationship between the air passed to the engine and the oil atomized may obtain; and in order to employ the 75 variable carburetive method of motor control, it is requisite that means be provided for automatically controlling the operation of the valve 5 according to the variations in engine suction, and that means be further 80 provided for manually controlling the operation to vary the rate of carburation at will. The ordinary form of valve (the disk) will 85 not perform this function satisfactorily, as the difference of pressure actuating the same 90 is at a maximum when the valve is closed and become progressively decreased, as the valve opens. When such a valve is controlled directly by a spring, then, when the 95 pressure against the valve is at a maximum, 100 the spring tension is at a minimum, and as the pressure against the valve decreases, the spring tension is at a minimum, and as the pressure against the valve decreases, the spring tension increases, so that there is but 105 one critical point in the travel of the valve where the two forces are in balance, and as this critical condition cannot continue, the valve is subject alternately to both forces 110 and reciprocates or chatters, causing an un- 115 steady delivery of air. It will also be appreciated that such a valve has no definite volumetric efficiency. To obviate this defect I have devised the form of valve shown, which consists of two nozzles or air passages, one 115 (32) stationary, and the other, the valve proper (5) movable. When closed the valve is subject to the full difference of static 120 pressure between its inner and outer surfaces, but as it begins to open, the pressure 125 falls in both nozzles, the valve proper being subject to the static pressure existing above the discharge orifice of the stationary nozzle, and, as the direction of the air current is changed 180° it is also subject to a dynamic pressure, due to the momentum of the air particles at the velocity induced by the difference of static pressure, and when resisted by a spring, the tension of which varies directly as the degree of flexure, it 130

will rise a definite height and discharge a determinable volume of air for each degree of difference of pressure. As the differential pressure operates to induce the flow of oil 5 to the atomizer, and as definite ratios of carburation must obtain, the volume of air passed by the valve must be coöordinated to the volume of oil which can be caused to flow in the atomizer. This oil volume will vary 10 with a definite area of opening between the oil tube and the spray-head, as the square root of the difference of pressure, increasing but twice in velocity and volume when the pressure is increased in the ratio 1:4. It 15 is obvious therefore that if the differential valve will pass eight volumes with a four fold increase of pressure while the oil volume increases only two fold, a decrease in the rate of carburation would ensue; this condition 20 is not desirable as a definite rate of carburation must obtain for each degree of difference of pressure. It is therefore necessary to provide a means for decreasing the differential valve opening, reducing the same so 25 that the volume of air passed will be in proper proportion to the volume of oil discharged; and therefore I introduce a means of manually varying the rates of carburation to effect the power and speed variations 30 of the motor by changing the relative position of the valve and its spring, manually, as regards the area of its opening, and thereby decrease the volume of air so as to cause a definite ratio of carburation to obtain for 35 each degree pressure variation, this manual control being conveniently effected by connecting the differential and throttle valves, with a spring 6 to increase the resistance of the former as the latter is opened.

40 The operation of the carbureter is as follows: A reduced pressure being induced by the operation of the engine, air flows into the carbureter and oil flows to the atomizer, the differential valve 5 passing a definite 45 volume of air, and the oil regulating device a definite volume of oil, establishing a specific rate of carburation. To increase the power of the motor the position of the differential valve and its controlling spring is 50 controlled, manually, by moving the same downward, by means of the lever 10, which opens the inlet or throttle valve 8 and at the same time tends to close the valve 5, which, reducing the relative volume of air passing 55 said valve 5, increases the differential pressure between the chamber 31 (and oil reservoir) and the chambers 33 and 38, causing an increased flow of oil, which, increasing the rate of carburation, causes an increase of power. A decrease of power is 60 effected by reversing the former movement. It is therefore evident that as the air volume and the oil volume are coöordinated and for a given differential pressure are each identi- 65 cal in proportion, that it is possible to main-

tain a maximum or a minimum rate of carburation, at full speed, and a maximum or a minimum rate at low speed, and any other degree of carburation at any speed. The relative degree of carburation being manually controlled, the automatic action of the differential valve and the oil regulating mechanism maintain such rate, while varying the relative volumes of air and oil delivered to respond to the varying speed 70 changes of the motor.

The action of the carbureter is such that it requires the lowest possible vacuum to operate; and the speed or power variation is effected in a manner to secure the highest 80 thermal efficiency of operation, while the method of control will permit of a great degree of flexibility at low speeds. The operation being mechanical is independent of the relative volatility of the fuel oil used, 85 and of the temperature and degree of humidity of the atmosphere.

I claim:

1. A carbureter having high and low pressure chambers with a constricted passage 90 therebetween, an oil nozzle discharging at said passage, a by-pass connecting the high and low pressure chambers around said passage, and a valve in said by-pass, comprising a nozzle, and an inverted cup-shaped 95 member surrounding and spaced from said nozzle, and means tending to close said cup shaped member.

2. A carbureter, having high and low pressure chambers with a constricted passage 100 therebetween, an oil nozzle discharging at said passage, a by-pass connecting the high and low pressure chambers around said passage, and a valve in said by-pass, comprising a nozzle, and an inverted cup shaped 105 member surrounding and spaced from said nozzle, the effective area of the space between the nozzle and the cup shaped member being substantially equal to the effective area of the nozzle, and means to close the 110 cup shaped member.

3. In a carbureter, the combination of an oil nozzle, an air passage, having a contracted part surrounding said nozzle, a throttle controlling the inlet to said passage, a 115 vacuum chamber with an outlet pipe into which said nozzle discharges, said chamber and pipe being unobstructed beyond said nozzle, and a by-pass leading from the inlet end of said passage and terminating in a 120 secondary annular air outlet surrounding said contracted part of the air passage and spray nozzle and communicating with the vacuum chamber to form a continuous annular enveloping air current in said chamber around the fluid drawn from the nozzle, to prevent precipitation of liquid particles on the surface of the vacuum chamber.

4. In a carbureter, the combination of a 125 passage having an air inlet and throttle at 130

one end and an outlet at the other end, an oil nozzle discharging into said passage, a by-pass extending around said nozzle, whereby part of the flow of air will be 5 through said by-pass, an automatic valve in said by-pass and controlling said flow, a spring pressing against the valve and tending to close the same, and means to manually increase the tension of said spring, according to the extent of opening of the 10 throttle.

5. In a carbureter, the combination of a passage having an air inlet at one end and an outlet at the other end, an oil nozzle dis- 15 charging into said passage, a by-pass extending around said nozzle, whereby part of the flow of air will be through said by-pass, an automatic valve in said by-pass and controlling said flow, a spring pressing against 20 the valve and tending to close the same, and a manually operated throttle located at the air inlet, and connected through said spring with said automatic valve for control there- with.

25. 6. In a carbureter, the combination of a mixing chamber, means to supply oil thereto, a primary air supply thereto, an additional air passage leading to the mixing chamber, and a valve controlling said pas- 30 sage, said valve comprising a stationary nozzle, a movable cupped member or nozzle extending around said stationary nozzle and spaced therefrom, whereby the course of the air current is reversed as it passes 35 through said nozzles, and means tending to close the movable nozzle.

7. In a carbureter, the combination of a mixing chamber, means to supply oil thereto, an air throttling valve communicating

with the chamber, an auxiliary yielding air 40 valve communicating with the chamber, and manually operated means including a connection between the throttling valve and the auxiliary valve, to increase the tension of the auxiliary valve in proportion to the 45 extent of opening of the throttling valve.

8. In a carbureter, the combination of a low pressure chamber, a spring controlled auxiliary air valve thereto, an oil nozzle leading to said chamber, a yielding valve 50 controlling the discharge from said nozzle, and means to progressively increase the resistance of the oil valve in a definite proportion corresponding to the increase in tension of the spring of the auxiliary air valve 55 incident to reduction of pressure in said chamber.

9. In a carbureter, the combination of a mixing chamber, means to supply oil thereto, a primary air supply thereto, an additional air passage leading to the mixing chamber, said air passage being provided with a wall extending in the direction of the flow of air, a valve for said air passage and means tending to close said valve, said valve comprising a surface against which the air impinges, and a flange extending toward, substantially parallel with and spaced from said wall, whereby the course 60 of the air current is reversed as it passes 65 said valve.

In testimony whereof, I affix my signature in presence of two witnesses.

WARD TEMPLE MIXSELL.
